UNITED STATES PATENT OFFICE.

HENRY P. KRAFT, OF RIDGEWOOD, NEW JERSEY.

DUST-CAP FOR TIRE-VALVES OR THE LIKE.

1,295,766.

Specification of Letters Patent. Patented Feb. 25, 1919.

Application filed May 18, 1917. Serial No. 169,384.

To all whom it may concern:

Be it known that I, HENRY P. KRAFT, a citizen of the United States of America, residing in Ridgewood, in the county of Bergen and State of New Jersey, have invented certain new and useful Improvements in Dust-Caps for Tire-Valves or the like, of which the following is a specification.

This invention relates to dust caps for tire valves or the like, and aims to provide certain improvements therein.

The present invention is directed particularly to a dust cap for valves which are used in connection with wire wheels, where in there is no wooden felly, the spokes of the wheel being connected directly to the metallic rim. In this type of rim it has been customary to use interchangeable valves of different lengths with the result that with the shorter valves there is, of course, much less projection inwardly beyond the rim than with the larger valves. In either case in the standard type of dust cap a long screwing operation is necessary which in the case of the larger sizes of valve becomes quite burdensome. According to the present invention I provide a cap which may be applied by a short screwing operation and as easily with long valves as with short valves. To this end I provide a telescopic cap, the closed section of which is adapted to screw onto the end of the body of the shell as distinguished from the nipple, and the open section of which is adapted to be extended along the closed section and to frictionally grasp the body of the valve shell to maintain it in position.

The invention also includes other features of improvement which will be hereinafter more fully described.

Referring to the drawings which illustrate one form of the invention,—

Figure 1 is a view of the tire rim, partly in section, the valve shell being shown in elevation and the dust cap embodying the present invention shown in diametrical section.

Fig. 2 is an elevation showing the cap as applied to a long valve.

Fig. 3 is an end view of the cap.

Referring to the drawings, let A indicate a pneumatic tire shown as held upon a metallic rim B. The valve shell or casing is indicated at C and the rim nut at D. In Fig. 1 the valve shell extends inwardly be-

yond the rim a considerably greater distance than in Fig. 2, due to the difference in length of the two valves.

E indicates the dust cap as a whole which is shown as comprising a cap section F and a sleeve section G. The cap section is preferably arranged within the sleeve section and is provided with an internal screw-thread H which engages the thread on the valve shell or casing. The sleeve section G is adapted to telescope with the cap section and is preferably provided at its inner end with a frictional means adapted to slide along the exterior of the valve casing and hold its position by frictional engagement. In the construction shown this is provided by forming the end of the sleeve section with a reduced portion I which is slotted to form spring arms J. The screw-threaded exterior of the valve casing provides a surface which is well adapted for a frictional engagement with the sleeve.

Preferably in order to reduce the time required to apply the cap to a minimum, the screw-threaded portion H is made short and is arranged within the cap section F at a considerable distance from the end K thereof. Between the end and the screw-thread the diameter of the cap section is enlarged so that it will slip over the casing without requiring to be rotated. It is preferable also that the cap section shall be provided with a stop which will limit its onward movement upon the valve shell. The simplest form of stop is that shown in which the metal beyond the end of the thread L prevents the further screwing on of the cap section. This is so arranged that the cap section will not interfere with the valve cap M. By the use of a stop the cap can only be screwed on a few turns which enables it to be seated in position with rapidity, and the stop also enables the cap section to be tightened in place so that it will not work loose in use. In order to produce a construction in which the inner parts slide easily on each other, the inner end of the cap section is provided with a flange O and the sleeve section is made of sufficient internal diameter to pass over the flange; the outer end of the sleeve is also provided with a flange P which is inturned so that it engages the exterior of the cap section. This also prevents separation of the sections.

It will be seen by reference to Fig. 1 that

the cap section always occupies a definite position with regard to the outer end of the valve shell, irrespective of the length of the latter. When this is adjusted in place the 5 sleeve G is slid down until its end I contacts with the rim nut. The cap is hence securely held against loss by a screw-threaded connection while at the same time it is capable of expanding and contracting in 10 length, and in any position forms an efficient dust-excluding casing for the valve stem.

While I have shown and described one form of the invention, it will be understood that I do not wish to be limited thereto, since 15 various changes may be made therein without departing from the spirit of the invention.

What I claim is:—

1. A dust cap comprising a cap portion 20 having an internal screw-thread, and an adjustable telescopic portion held in place by frictional engagement having means at its inner end for engaging a valve shell, said means being adapted to slide along the valve 25 shell.

2. A dust cap comprising a cap portion having an internal screw-thread, and a telescopic portion having means at its inner end for engaging a valve shell, said means

being adapted to slide along the valve shell, 30 and said means comprising spring arms.

3. A dust cap comprising a cap portion having an internal screw-thread, a portion of enlarged internal diameter between said screw-thread and the inner end of the cap 35 portion, and an adjustable telescopic portion adapted to slide on said cap portion and held in place by frictional engagement.

4. A dust cap comprising a cap portion having an internal screw-thread adapted to 40 engage a valve shell, a stop for limiting the onward movement of said cap portion, and a telescopic portion sliding on said cap portion, and having means for frictionally engaging a valve shell. 45

5. A dust cap having a screw-threaded cap portion and a telescoping portion sliding on said cap portion, said telescoping portion having spring arms adapted to frictionally engage a valve shell. 50

6. A dust cap having a cap portion F having a flange O and internal screw-thread H, and a sleeve portion G having a flange P and a contracted portion I formed with spring arms. 55

In witness whereof, I have hereunto signed my name.

HENRY P. KRAFT.
